CARL W. SPOHR, OF CHICAGO, ILLINOIS, ASSIGNOR TO WILLIAMS, CAMP AND BRADBURY, OF CHICAGO, ILLINOIS, A COPARTNERSHIP COMPOSED OF LYNN A. WILLIAMS, CURTIS B. CAMP, AND CLIFFORD C. BRADBURY

CARBURETOR-CONTROLLING DEVICE

Application filed January 25, 1926. Serial No. 83,551.

My invention relates to control device for use with choke valves of the carburetor of internal combustion engines, especially as used on automotive vehicles.

5 It is an object of my invention to provide a simple choke valve control device in which fine adjustments of the choke valve may be accurately made and in which the tendency of the control wire to bind in its guiding tube 10 is practically eliminated.

Other objects will appear from the following description, reference being made to the accompanying drawings in which

Fig. 1 is a front elevation; and,

15 Fig. 2 is a bottom plan view.

As shown in the drawings, the supporting bracket 3 is secured by bolts 4 to an automobile instrument board 5 at its lower edge.

An arm 3^a, projecting rearwardly from the 20 bracket 3, is vertically drilled at its end to receive a flat headed pin 6, upon which the control lever 7 is pivoted. A spring 8, coiled around the pin 6, is compressed between the lower surface of the lever 7 and a washer 9,

25 which may be grooved or flanged so as to form a secure seat for the end of the spring

8. Any suitable means, such as the cotter pin 10, may be employed to hold the washer in position. This spring is for the purpose 30 of providing a small amount of friction between the lever 7 and the bracket 3^b so as to prevent the lever from being displaced by the vibrations of the automobile.

The usual brass tube 11, which serves as a 35 guide for the resilient actuating wire 12, is secured in a clamp 13 which is fastened to the flange 3^b by a screw 14. The clamp 13 has a downwardly projecting flange 13^a which engages the edge of the flange 3^b and prevents 40 rotative movement of the clamp.

It is to be understood that one end of the wire 12 is connected to the carburetor air intake or choke valve in the usual manner. The 45 other end is secured to the lever 7, fitting into a hole drilled perpendicularly to the longitudinal axis of the lever, and secured thereto by a set screw 15. The end of the wire 12 will thus be held in a position tangential to the arc through which the point at

which it is attached to the lever 7 travels as the lever is swung on its pivot pin 6.

It will be noted that the tube 11 is bent along the arc of the circle, having its center at the pivot point of the lever 7 and having a radius equal to the distance between the pivot point and the point at which the wire 12 is attached to the lever 7. Thus the wire 12 will also be bent into an arc of this circle since the hole in the lever 7 in which its end is held is tangential to this arc. The usual tendency of the wire to bind and buckle is thus eliminated.

The lever 7 extends through a slot 3^c in the bracket 3 and terminates in an enlarged finger piece 7^a. The face of the bracket is graduated adjacent the slot 3^c and on indicia "Lean—Rich" raised on the face of the bracket to aid in the proper positioning of the lever. In the use of the device, the air inlet or choke valve may be easily adjusted to suit weather and other variable conditions of operation and will be held in adjusted position by the friction caused by the pressure of spring 8 and by the friction of the wire 12 in its tube 11.

While the device is shown and described as attached to the actuating end of the control wire, it will be apparent that it may also be used at the actuated end of the control wire, at the carburetor or similar device. Suitable changes would be necessary in the design of the device in such instances to adapt it for the particular use to which it may be put, but such changes in design may be readily made by any skilled mechanic. It is therefore not considered necessary to show or describe the possible varieties of constructions in which my invention may be embodied. The principles of my invention may be utilized in any construction where it is desired to mechanically connect a pivotally movable part with another element by a guided resilient wire.

While the form of mechanism herein shown and described is admirably adapted to fulfill the objects primarily stated, it is to be expressly understood that it is not intended to confine the invention to the one use or to the one form of embodiment herein disclosed and

that the invention is susceptible of embodiment in various forms, and use in various connections, all coming within the scope of the claims which follow.

5 I claim:

1. In a device of the class described, a bracket, a control lever pivoted to said bracket and pressed into frictional contact therewith, an arcuate guide tube fixed to said bracket, a resilient control wire guided within said tube and having its end projecting therefrom, and means to secure the end only of said wire to said lever so as to hold the portion projecting from the tube in arcuate shape to facilitate reciprocation of said wire in said tube.
2. In a device of the class described, the combination of a bracket, a control lever pivotally mounted on said bracket, a flexible control wire, an arcuate guide tube therefor secured to said bracket and having its curvature concentric with the axis of said lever, said lever having transverse bore therethrough having its axis tangential to the arcuate path of the lever at that point for receiving the end only of said flexible wire to hold the wire in arcuate shape to coincide with the curvature of said guide tube.

In witness whereof, I hereunto subscribe
30 my name this 21 day of January, 1926.

CARL W. SPOHR.
